Specification of Letters Patent.

Patented July 3, 1917.

Application filed June 16, 1916. Serial No. 104,018.

To all whom it may concern:

Be it known that I, GEORGE D. HOWARD, a citizen of the United States, residing at Salisbury, in the county of Rowan and State 5 of North Carolina, have invented new and useful Improvements in Bearings, of which the following is a specification.

This invention relates to improvements in crushing machines of the gyratory type, and 10 is particularly directed to means for facilitating the removal and replacement of the eccentric bearing for the gyratory shaft of such machines.

In crushing machines of this class the gyratory shaft, carrying the crusher head, is supported or suspended from its outer end and has its lower end received in an eccentric bearing that is arranged in an oil well provided in the bottom plate of the machine 20 and to this bearing is secured the beveled toothed operating wheel for the shaft, the constant wear to which the eccentric bearing is subject soon results in serious damage thereto, and consequently the necessity for 25 the frequent replacement of the worn bearing by a new one. The removal of an old bearing constitutes a task of considerable magnitude, it being understood that the machine is of a heavy construction and that 30 the bottom plate and the drive wheel are of such size, proportion and weight whereby the same can be handled by a man of average strength, but with the ordinary construction of this class of crushers, its necessary to re- 35 move the plate and consequently the bearing which rests in the well of the said plate and the heavy drive wheel which is connected with the bearing. To change the bearing in a crusher of the old type of such 40 machines would require the work of a large force of laborers for approximately twenty-four hours, while to change the eccentric upon the improved class of these machines, on which certain provisions are made for 45 the removal of the actuating means of the machine, the same force of laborers are required, but the work can be accomplished in approximately eight hours' time.

With my improvement I aim to produce a 50 construction wherein the parts are so constructed and arranged that the beveled operating wheel is keyed to the eccentric, and the said key being accessible from the exterior of the machine, through the opening 55 through which the power shaft, having the

pinion which co-acts with the referred to beveled operating wheel, passes so that the same may be readily removed when required and I connect the eccentric bearing with the operating wheel in such a manner as to 60 permit of the ready disassociation of these members when the locking key is removed, and also I provide the bottom of the well at the end of bottom plate of the machine with a removable closure fastened thereto 65 by cap screws, whereby the said closure may be readily detached when desired to permit of the removal of the eccentric through the well of the said bottom plate without otherwise interfering with the operating wheel, 70 the shaft or any of the actuating mechanism of the crusher, and wherein an eccentric can be replaced at a period of time which from actual test will not require over one hour.

Other objects and advantages of my construction will appear to those skilled in the art to which such invention appertains from the accompanying description and from an inspection of the drawings forming part of 80 this specification.

In the said drawings:

Figure 1 is a vertical transverse sectional view through the lower portion of a crushing machine having a gyratory shaft and provided with my improvement, the dotted lines illustrating the eccentric bearing removed therefrom,

Fig. 2 is an enlarged central longitudinal sectional view of the eccentric,

Fig. 3 is a plan view of the eccentric,

Fig. 4 is a sectional view approximately on the line 4—4 of Fig. 2,

Fig. 5 is a face view of the bottom plate for the machine constructed in accordance 95 with the idea,

Fig. 6 is a sectional view approximately on the line 6—6 of Fig. 5,

Fig. 7 is a similar sectional view approximately on the line 7—7 of Fig. 5, and 100

Fig. 8 is a horizontal sectional view approximately on the line 8—8 of Fig. 1.

For the purpose of illustration I have found it necessary to show only the lower portion of a crushing machine of the gyratory type, such, for instance, as that in which the gyratory shaft 10 which carries the crusher head (not shown) is supported or suspended from its top and disposed centrally of the machine 11. The shell of the 110

2

machine is provided with the usual open bottom which, in the present instance, is closed by a bottom plate 12 constructed in accordance with my invention, the said bottom plate being bolted or otherwise secured to the machine frame or shell and being centrally provided with the depending sleeve portion providing the well 13. The well 13, in the present instance, has its lower and 10 open portion closed by a plate 14, the plate being secured to the said well by cap screws 15, and the plate 14 is preferably centrally provided with a threaded aperture forming an oil outlet, which aperture is closed by a 15 threaded plug 16. The inner face of the plate 12, above the well 13, is centrally formed with an annular extension or flange 17 as well as with an annular lip 18 surrounding the said flange and contacting with 20 the inner edge of the wall provided by the opening closed by the plate 12. Radially disposed ribs 19 are arranged between the flange 17 and the lip 18. The flange 17 is also surrounded by an annular member 20 25 which is also connected by the ribs 19, and the plate 12, between the flange and the annular member 20 is provided with a plurality of vertically disposed ports 21 having spaced outlet openings 22 communicating 30 with the bore of the well 13, while the said plate upon its upper face is provided with an inlet or duct 23 having a pipe member 24 connected therewith, and the said pipe member communicates with a source of oil 35 supply whereby a lubricant can be fed to the well 13 and to the bearing member as well as the bushing for the bearing member which will presently be described.

The shell of the device, at the bottom therefore, is provided upon its side opposite the chute chamber 25 with an opening 26 within which is arranged a bearing 27 and a horizontally disposed power shaft 28 that has its inner end provided with a beveled toothed 40 pinion 29 which meshes with the beveled toothed wheel 30. The bore of the wheel 30 receives the reduced end of the gyratory shaft 10, the said bore, however, being of a materially greater area than the cross section 45 diameter of the end of the shaft 10 and this bore is provided with right angularly disposed vertically arranged grooves 31-31. The hub 32 of the operating wheel 30 rests upon the flange 17 of the plate 12 and bears 50 upon anti-frictional members arranged between the said hub and the said flange. The bore of the hub has passed therethrough the upper and widened end of a bearing member 33, the said bearing being provided with an 55 eccentrically arranged bore 34 which receives the reduced end 35 of the operating shaft 10 as well as the reduced extension 36 of the said shaft. It will thus be noted 60 that the bore of the bearing 33 is of two diameters, the lower portion of the said 65 bore being indicated for distinction by the numeral 37 and this portion of the bearing is provided with a plurality of ports 38 which communicate with the oil ports 22 in the well or sleeve 13 of the plate 12. The 70 lower portion 37 of the bearing 33 also, for approximately one-half of its diameter, is provided with horizontally disposed reduced substantially semi-annular members 39 around which is arranged a bearing surface 75 40 such, for instance, as Babbitt metal which is shaped to agree with the circumferential shape of the bore of the bearing and which receives the thrust from the reduced extension 36 of the gyratory shaft 10 to prolong 80 the life of the bearing. The upper end of the eccentric bearing 33 is provided with right angularly disposed outwardly projecting lugs 41-41 which are of a size to be received in the grooves 31 in the bore of the 85 hub 32 of the operating wheel 30, when the bearing is rotated to bring its lugs into alinement with the said grooves. The upper end or hub of the bearing 33, between two of the referred to lugs 41, is provided with 90 a vertically disposed depression or groove 42 which is adapted to register with one of the grooves 31 in the bore of the operating wheel 30, and these registering grooves are adapted to receive a key 43 which is passed 95 through the openings 26 in the shell of the machine and which key effectively locks the operating wheel 30 to the bearing 33. By reference to the drawings it will be noted that the shouldered end 35 of the gyratory 100 shaft and its reduced extension 36 are loosely positioned within the bearing so that other gyratory or rocking movement of the shaft will not be interfered with, but in order to effectively sustain the bearing in the well 105 33, I provide a sleeve or bushing member 44 which surrounds the lower or reduced end of the said bearing and which rests upon the closure plate 14 of the well 13 of the bottom plate 12. To secure this bushing 44 11 I provide the same with a transverse opening and I also provide the well with an opening which is adapted to aline with the said transverse opening and I pass through these registering openings the shank of a 11 headed bolt 45, the threaded end of the bolt having screwed thereon a nut 46.

As previously stated the thrust or strain to which the bearing is subjected by the gyratory shaft soon results in serious damage 12 to the bearing and consequently the replacing thereof by a new bearing. To accomplish this I remove the closure plate 14 by unscrewing the cap screws 15. I then remove the bolt 45 from the well and from 13 its engagement with the bushing 44. Then I pass one hand through the opening 26 and withdraw the key 43 which connects the operating wheel to the bearing. I then turn 14 the bushing until the lugs 41 registers 15

with the grooves 31 in the hub of the operating wheel 30. This permits of the bearing 33 dropping through the well 13 of the bottom plate 12 and, as also previously stated, I have found from practice that the removal of the old bearing and the replacing of a new bearing therefor can be accomplished by a single man in less than one hour's time.

10 Having thus described the invention, what is claimed as new is:

1. In combination with a power wheel and a shaft having a reduced end extending through the bore of the said power wheel, 15 of a bearing member having an eccentric bore to receive the end of the shaft, said bearing member having its upper end provided with outstanding lugs which normally rest upon the top of the power wheel and 20 which when the bearing is turned upon the said power wheel will register with the grooves in the bore of the said wheel, whereby to permit of the disassociation of the bearing from the power wheel and from 25 the shaft, and means for normally locking the bearing in the bore of the power wheel.

2. In combination with a power wheel, a shaft having a reduced end extending through the bore of the said wheel and the 30 bore of the said wheel being provided with longitudinal grooves, of a bearing having a reduced and eccentrically arranged bore to receive the reduced end of the shaft and said bearing designed to receive the reduced 35 end of the shaft, the bearing having its upper end provided with outstanding lugs which normally rest upon the upper face of the power wheel, the upper enlarged portion of the bearing having a longitudinal 40 groove designed to register with one of the

grooves in the bore of the power wheel, a key between this groove and one of the grooves in the bore of the power wheel, and the lugs of the said bearing being of a number and of a size to freely slide through the 45 grooves in the bore of the power wheel when the bearing is turned upon the power wheel to bring the lugs into alignment with the said grooves upon the removal of the key.

3. In combination with a plate having a depending sleeve, a removable cap plate for the sleeve, a shaft having a reduced end received in the sleeve, and a power wheel having a bore surrounding the reduced end of the shaft and the said bore being formed 55 with longitudinally extending grooves, of a bearing member having an upper enlarged portion received in the bore of the power wheel and the said upper portion provided with outstanding lugs resting upon the 60 power wheel and said lugs being spaced whereby the same may be brought to register with the grooves in the bore of the power wheel to permit of the separation of the said bearing from the said wheel, said bearing 65 having its enlarged portion provided with a groove designed to register with one of the grooves in the bore of the power wheel, a key removably received in the alining 70 grooves, said bearing having an eccentric bore to receive the end of the shaft, a bushing surrounding the reduced end of the bearing and resting upon the cap plate of the sleeve, and an element passing transversely through the sleeve and bushing below the bearing and the reduced end of the shaft for securing the bushing in the sleeve.

In testimony whereof I affix my signature.

GEORGE D. HOWARD.
